UNITED STATES PATENT OFFICE

2,619,882

CARTON ERECTING MACHINE

James Oscar Rohdin, Staket, Sweden, assignor
to Esselte forpackning ab, Norrkoping, Sweden,
a corporation of Sweden

Application August 31, 1950, Serial No. 182,542
In Sweden January 26, 1948

2 Claims. (Cl. 93—53)

1

This invention relates to machines for packeting commodities in collapsible rectangular cartons made from cardboard, stiff paper, or the like, the cartons being of the kind having foldable flaps at one or each end, and particularly cartons of the kind described in United States Patent No. 2,427,858. The cartons are usually stored in a flat or collapsed condition, and it is necessary to extend them to the rectangular form prior to the packeting operations.

The object of the present invention is to enable the feeding of the cartons to a carton-carrier, and the subsequent extending of the cartons, to be effected automatically in a convenient manner.

The invention comprises a machine having combined therewith, a carton carrier movable in a step-by-step manner and provided with rectangular recesses for reception of the cartons, feeding means whereby the cartons are fed individually from a magazine in the collapsed condition, so that each carton is initially placed in an oblique position across a recess in the carrier, and an obstructor which when encountered by an edge of the carton during movement of the carrier causes the carton to be extended and pressed into the recess.

In the accompanying drawings:

Figure 1 is a perspective view of a carton of the kind above described, one end being shown closed and the other open.

Figure 2 is a plan illustrating a portion of a packeting machine embodying the invention, the machine being of the kind in which a rotary carton carrier is employed.

Figure 3 is a side elevation illustrating the application of the invention to a machine in which the carton carrier is arranged to move with a linear motion.

Figure 4 is a section of a portion of the carton feeding mechanism in a plane parallel to the direction of feed.

Figure 5 is a section of the means for extending the flaps at the ends of the carton.

Figures 6 and 7 are respectively plan and side elevation illustrating diagrammatically the action of the flap-extending means.

Figure 8 is a section on the line 8—8 Figure 2.

Figure 9 is a perspective view illustrating the action of a carton-opening knife.

Referring to Figure 1, the carton there shown comprises a rectangular body part *a* made from cardboard or stiff paper, and having at each end a flap *b* which can be turned down to a position at right angles to the body part as shown.

2

The other end flaps as *c*, *d* are united at their corner edges and are adapted to be folded down over the body part, prior to the folding over them of the flaps *b* in the packeting operation. Also 5 the body part is provided with a thin paper lining *e* which at the position shown may have formed therein a notch *f* for the purpose hereinafter mentioned. Cartons of the kind shown in Figure 1 are usually supplied and stored in a 10 flattened or collapsed condition.

As already stated the purpose of the present invention is to feed the cartons to a carrier and subsequently extend the cartons prior to the filling and subsequent closing of the ends of the 15 cartons.

Referring to Figure 2, this shows a portion of a packeting machine of the kind in which a rotary carton carrier *g* is employed, this being operable in a step-by-step manner by any convenient means. In the periphery of the carrier are formed rectangular recesses *h* for the reception of the cartons. Adjacent to the carrier is mounted a magazine *i* for the reception of a stack of collapsed cartons *a* against which presses 20 a weight or spring loaded pusher *j*. Adjacent to the forward end of the magazine is mounted a 25 slideable member *k* against which the stack of cartons is pressed by the pusher, and which is operable by an oscillatory toothed segment *m* 30 engaging a rack *n*, the member *k* being provided with a feeder *o* by which the cartons can be individually and successively fed from the magazine to an intermediate position between the magazine *i* and the carrier *g*. Also there is provided on the slideable member *k* and near its forward end, a spring loaded tooth *p* (Figure 4) for moving the carton from the said intermediate position to the carrier.

On a bracket *q* situated between the magazine *i* and the rotary carrier *g*, and between which and a supporting surface *r* (Figure 4), there is pivotally mounted a catch *s* loaded by a spring *t* for preventing accidental return movement of the carton. Also there are mounted on the upper and lower sides of the bracket *q* a pair of 40 guide bars *u* (Figures 2 and 5) which are adjustably attached to the bracket *q* by arms *v*, and on the forward end of each guide bar is pivotally mounted a finger *w*. The purpose of the guide 45 bars *u* is to extend each of the flaps *b* of the carton by turning it through a right angle while the carton is being fed from the magazine to the said intermediate position. During this movement the fingers *w* pass behind the flaps *b* as 50 shown in Figures 6 and 7, and cause the flaps to 55

be bent over, the flaps being then held in this condition by the bars *u* as shown in Figures 1 and 5.

From the said intermediate position the carton is fed by the action of the tooth *p* (Figure 4) to the adjacent recess *h* in the rotary carrier so that it lies obliquely across the recess as shown in Figure 2. When in this position the carton is temporarily held in by a spring loaded presser-finger *2* pivotally attached at its end *3* to the part *q*, and arranged to exert a lateral pressure on the carton for pressing it towards the entrance of the adjacent guide arranged at the periphery of the rotary carrier. The guide consists of a fixed segmental member *4* of hollow construction (Figure 8) on which are attached segmental plates *5* which with the part *4* form narrow guide channels along which the flaps *b* can move when the carton is advanced to its other positions by the carrier. Also within the guide *4* is pivotally mounted a bell crank lever *6* one arm of which is held in contact with an adjustable stop *7* by a spring *8*, and on the other arm is carried an obstructor in the form of a freely rotatable roller *9* which preferably has a serrated or knurled periphery, and which is encountered by the forward edge of the carton after it has been moved by the rotary carrier from its first to its second position, as shown at *a¹* in Figure 2. During the next movement of the carrier, the carton is moved past the roller and is thereby caused to assume its extended or opened condition; also it is pressed by the roller into its recess in the carrier as shown at *a²*. To ensure that the carton shall be pressed properly into the carrier recess, a spring blade *12* is provided in the guide *4* as shown in Figure 2, and arranged to exert pressure on the outer face of the carton.

During the further movements of the table the flaps at the lower end of the carton are folded over, the contents are introduced, and the flaps at the upper end are folded over, but the means for effecting these operations form no part of the present invention.

It will be understood, that during each rest interval of the rotary carrier, a carton is fed into an empty recess in the carrier as above described.

To obviate risk of interference with the proper opening of the carton under the action of the roller *9*, due to adherence of the continuous faces of the lining *e*, it may be desirable to effect a preliminary separation of these faces by means of a knife. This operation may be performed either before the cartons are placed in the magazine, or when the cartons approach the roller *9*. Further this operation may be effected by manual or automatic actuation of a knife, and to facilitate insertion of the knife, the projecting end of the lining may be formed with a gap *f* as shown in Figures 1 and 9, the knife being indicated by *10* in Figure 9.

Whilst in the foregoing the invention has been described as applied to a machine having an intermittently rotatable carton carrier, it may be applied in an essentially similar manner to a machine having a carton carrier which is moved along a rectilinear path. Such an application is illustrated diagrammatically at Figure 3, which with the aid of the above description is self-explanatory.

What I claim is:

1. In a packeting machine the combination of a magazine for receiving a pile of collapsed cartons, a carton carrier movable in a step-by-step manner and formed with rectangular recesses in its peripheral edge for the reception of the cartons, means for feeding the cartons, one by one, from the magazine to the recesses of the carrier, said means comprising a reciprocable slide member forming an end wall of the magazine against which the pile of cartons therein is pressed, means on said slide member for feeding the carton in contact with said slide member from the magazine to an intermediate position between the magazine and the carrier on each operative stroke of the slide member, other means on said slide member for simultaneously feeding another carton from said intermediate position to a diagonal position in a recess of the carrier with one end portion of the carton projecting beyond the front edge of the recess, a stationary guiding device for the projecting portion of the carton, a spring controlled lever pivoted to said guiding device, and a roller rotatably mounted in said lever for projecting into the path of said portion of the carton, said roller being adapted to catch the projecting end of the carton and temporarily hold it against movement with the carrier for extending the collapsed carton to open it and cause it to fit into the recess.

2. In a packeting machine as claimed in claim 1, the further characteristic feature that means are provided at the said intermediate position for bending flaps of the collapsed carton to positions at right angles thereto, said means comprising guide-bars each shaped to effect bending of a flap and a pivoted finger at the end of each such bar for engaging the flap and initially bend it into contact with the respective guide bar.

JAMES OSCAR ROHDIN.
